H. D. COTTRELL

LOOSE LEAF BINDER

Filed Jan. 15, 1925

Patented Apr. 24, 1928.

1,667,511

UNITED STATES PATENT OFFICE.

HOLLAND D. COTTRELL, OF DETROIT, MICHIGAN.

LOOSE-LEAF BINDER.

Application filed January 15, 1925. Serial No. 2,469.

This invention relates to loose leaf binders, and the object is to provide a simple and highly efficient binder of inexpensive construction adapted to be made in a very cheap 5 form as well as in the more expensive forms and in various sizes.

A feature of the invention is in the provision of straps or similar elements fixedly attached to the opposite cover members in a 10 manner to achieve an object of the invention—namely, to provide a means that will bind the leaves and without adjustment of the straps will open practically flat to permit removal or introduction of sheets. Hereto 15 fore, in binders of this class, straps have been used and adjusting devices employed to take up or release the straps depending on the quantity of leaves to be bound, and an object of this invention is to secure a construction in which straps or the like are 20 fixedly attached at the opposite ends and, due to the arrangement, tend to bind the sheets between the covers whether small or large in number and that is readily released 25 from binding position to one in which the straps are relieved of tension permitting the binder to be opened practically flat as previously stated. These and other objects and 30 the various novel features of the invention 35 are hereinafter more fully described and claimed, and the preferred form of a loose leaf binder embodying my invention is shown in the accompanying drawings in which—

Fig. 1 is a perspective view of a binder in partially opened position.

Fig. 2 is a cross section of the binder in closed position.

Fig. 3 is a cross section of the binder in its 40 usual open position.

Fig. 4 is a cross section of the binder released to permit the leaves to lie flat.

Fig. 5 is a detail of a part of a leaf adapted for use with the binder and which is 45 notched at its rear edge to engage about the straps.

The binder consists of two cover members 1 and 2 between which is the channel pocket 3 substantially rectangular in form in cross 50 section, the cover members preferably being integral therewith and separated therefrom by scored lines at the points 4 and 5 providing hinge points for the covers and said channel pocket member being also preferably scored at 6 and 7 permitting the side walls of the cover to be turned as hereinafter

mentioned. These cover members may be of any approved material preferably somewhat flexible in character and in the more expensive forms may be of any desired material of 60 sufficient stiffness and covered with leather or other material to give the desired appearance. So far as this invention is concerned, it is not material whether or not the members 1 and 2 are integral with the channel 65 member 3, it being possible to secure the covers to the channel members in any approved manner or to reinforce the same with a leather or cloth hinge member. One of the cover members, as for instance the member 1, 70 is preferably provided with an interturned flap 8 which may be scored at 9 in practically hinged relation with the member 1 or may be attached thereto in any manner found desirable. The flap 8 serves as an attachment 75 for the strap ends to the cover 1 and, while the straps may be attached directly to the member 1 near its edge, it is preferred to use the flap as it enables the cover member to be flexed throughout its full length as indicated at the left side of Fig. 3 and the point 80 of connection of the straps with the cover member is not placed under an excessive strain in the flexing of the cover 1 and to which said point of connection would be subjected if connected directly with the edge of the member 1. To this flap 8 I therefore 85 preferably secure the straps 10, and these straps extend along the inside of the cover member 1 but unattached thereto and across 90 the channel pocket thru apertures provided at the hinge point 5 and are attached to the outer face of the other cover member 2. It is to be noted that the straps (which may be 95 of any desired material preferably non-elastic in form) are fixedly secured at the ends to the flap and cover member 2 and that the length of the straps is such that with the cover members in the position shown in Fig. 3, the hinge points 4 and 5 100 tend to be drawn together. There are preferably two of these straps 10 as indicated by dotted lines in Fig. 1.

Preferably I provide a secondary cover device formed of two members 11 and 12 105 which may be of paper or other desired material and formed, as by scoring, to provide a channel pocket 13 therebetween as may be understood from Fig. 3. Both these inner cover members 11 and 12 are apertured at the point of connection with the inner channel pocket to permit the straps to pass there- 110

through across the open edge of the channel pocket and the leaves to be bound in place. The leaves or sheets 14 have a pair of notches 15 opening through the edge to a longer slotted portion 16 which provide the inwardly extending parts 17 shown in Fig. 5. These leaves, being usually of paper, are sufficiently flexible to enable them to be positioned over the straps which is of a width practically equal to the slot 16, the part 17 engaging back of the strap and retaining the leaf in position as will be readily understood.

As previously stated, the cover members, at least that member provided with a flap, is more or less flexible in character and the straps are of a length tending to draw the hinge points 4 and 5 practically together when no leaves or sheets are in the pocket and when the sheets have been introduced, the cover 1 will be flexed to a greater or less degree drawing the hinge points 4 and 5 tightly into engagement therewith binding the leaves or sheets in place. It will be noted that a more or less number of leaves may be introduced without necessity of manually adjusting the straps, the arrangement providing a structure which is self-adjusting to hold one or a quantity of leaves.

Due to the straps 10 being attached at one end to the flap 8 and being otherwise unattached to the cover member 1 or the hinge points thereof, the said hinge point may be forced downward in the direction of the arrow shown in Fig. 3 thus forcing the channel pocket 3 downward and toward the other cover to the position shown in Fig. 4. This causes a release of the tension on the straps as the outer cover member 1 is moved a distance practically equal to the depth of the channel pocket. This releases the tension of the straps permitting them to lie comparatively loosely as will be understood from Fig. 4 and the leaves will also lie flat upon either of the cover members. This enables the pocket to be opened widely for removal or insertion of the sheets. This is the particular object of this invention to secure a self-adjusting binder that is capable of binding one or a considerable number of sheets with equal facility and still is capable of manipulation to release the tension and permitting the binder to lie practically flat when opened at any point for introduction or removal of the leaves. It is to be noted that the secondary cover members 11 and 12 are used principally to give a neat appearance to the binder and may be dispensed with if desired.

With the construction described, the binder when closed will lie practically flat as shown in Fig. 2 but may be opened as an ordinary book, the leaves being bound in the channel pocket and generally occupying practically the position indicated in Fig. 3 and yet by

merely moving the hinge point 4 out of the position shown in Fig. 3 to substantially that shown in Fig. 4, the tension is entirely relieved, the binding edges of the leaves are brought out of the pocket and may lie perfectly flat and loose on the straps permitting ready removal or insertion.

With a construction permitting the covers to be turned about the points 4, 5, 6 and 7, the structure upon movement of the hinge points 4 as stated readily assumes the position shown in Fig. 4 and is readily brought back to the position shown in Fig. 3 permitting the binder to be handled in the ordinary manner.

As previously stated, I prefer to form the cover members and pocket of a single piece of material scored at the points stated to enable the same to assume the position shown in Figs. 3 and 4 but the flap 8 may be made of a separate piece if desired and connected to the free edge of the cover member 1 and the channel pocket may also be formed of a separate piece to which the cover members are hinged respectively at the points 4 and 5.

In recapitulation, it is to be noted that by the flexing of one or both of the outer cover members a certain degree of slackness in the straps or binder elements is caused. This facilitates movement of the hinge point 4 and the channel pocket downward away from the bound edge of the inserted leaves which therefore may spring out or may be raised out of the outer channel in which they are normally housed. It is to be understood, however, that flexibility of one or both covers, although resulting in certain facility in manipulation of the device, is not an actual necessity inasmuch as with non-flexible covers the outer channel pocket may be manipulated as heretofore described and illustrated in Figs. 3 and 4 to release the straps and permit the leaves or sheets to lie flat and while retained in position by the straps are otherwise loose and in unbound relation. It is further a very simple matter to bring the leaves to binding condition by forcing the outer channel pocket from the position shown in Fig. 4 to that shown in Fig. 3. It is also to be observed that while I have shown an inner or secondary cover member provided with a channel pocket such member may be dispensed with without departing from the spirit of this invention as is set forth in the appended claims.

Having thus fully described my invention, its utility and mode of operation, what I claim and desire to secure by Letters Patent of the United States is—

1. A loose leaf binder comprising a pair of outer cover members, a channel pocket to which the inner edges of the cover members are hingedly secured, there being apertures provided at the hinge point between one of

the covers and the channel pocket, an inner cover member formed of a sheet of material shaped to provide a channel packet positioned in the channel pocket of the outer

5 cover members, the said inner cover members having apertures at each of the hinge points and a strap extending through each aperture of the outer cover member and through the apertures of the inner cover 10 member and connected with the free edge of the other outer cover member, the straps having the intermediate portions free from the outer cover members, and a series of leaves notched to engage about the straps 15 and positioned in the channel pocket of the inner cover member.

2. A loose leaf binder, comprising a pair of outer cover members formed to provide a channel pocket at the center, the covers 20 being hinged at the inner edges of the channel pocket, an inturned flap at the free edge of one of the outer cover members, a pair of inner cover members having a channel pocket nesting in the channel pocket of the outer 25 cover members, there being apertures in both the inner cover members at the hinge point and similar apertures at the hinge point of one of the outer cover members, a pair of straps secured to the flap of the outer 30 cover member and extending through the apertures and attached to the other outer cover, the straps having the intermediate portions unattached to the outer cover members, and a series of sheets positioned within 35 the inner cover member and notched to over the straps passing therethrough.

3. A loose leaf binder, comprising a pair of outer cover members formed to provide a channel pocket at the center, the covers being 40 hinged respectively to the edges of the channel pocket, an inturned flap at the free edge of one of the outer cover members, a pair of inner cover members of paper having a channel pocket positioned in the channel pocket 45 of the outer cover members, a pair of straps secured to the flap of the said cover member and extending through apertures provided at the edges of the channel pocket of the inner cover member and through apertures 50 at the hinge point of the outer cover member opposite the flap and being permanently attached thereto, the straps intermediate the ends being free from connection with the outer cover members.

55 4. In a loose leaf binder, the combination of a pair of outer cover members formed to provide a channel pocket at the center, an inturned flap at the free edge of one of the outer cover members, a pair of inner cover 60 members having a channel pocket positioned in the channel pocket of the outer cover member, a pair of straps attached to the

flap of the outer cover member, and extending through apertures provided at the channel pocket of the inner cover member and attached to the other outer cover member, said straps intermediate the ends being unattached to the outer cover member. 65

5. In a loose leaf binder, a pair of cover members formed to provide a channel pocket at the center, one of the cover members being provided with an inturned flap, an inner pair of cover members having a channel pocket seating in the channel pocket of the outer cover member, and straps permanently 70 attached to the flap of the outer cover member and extending across the channel pocket 75 of the inner cover member and permanently attached at the opposite ends to the other outer cover member, the straps intermediate 80 the ends being free from connection with the outer cover member.

6. In loose leaf binder, a pair of cover members, a channel pocket to the forward edges of which the respective cover members 85 are hinged, a number of straps secured at opposite ends to the respective cover members and extending across the channel pocket, the hinge point between one cover member and the respective side of the channel pocket 90 being free from the straps, a series of leaves having notched edges to engage about the straps, and being normally housed in the channel pocket, the construction permitting the said free edge of the channel pocket and connected edge of the respective cover member to be withdrawn from engagement with the leaves and turned about the other hinge point thereby releasing the straps and permitting the leaves to be separated at the 95 bound edge. 100

7. In a loose leaf binder, a pair of cover members, an integral channel pocket therebetween to the respective edges of which the cover members are hingedly connected there being apertures provided at the hinge point between one of the cover members and the channel pocket, a strap extending through each of the said apertures and attached directly to the cover member, the opposite ends of the straps being connected to the free edge of the other cover member the intermediate portion thereof being unattached to the cover member permitting the straps to be loosened, a series of leaves engaging the straps and free to slide thereon when the straps are in non-taut relation, and means whereby the straps may be released from taut relationship permitting removal or insertion of the leaves thereon. 115 120

In testimony whereof, I sign this specification.

HOLLAND D. COTTRELL.
